BALL SELF-LOCKING RELEASEABLE COUPLING

Robert James Brown, Los Angeles, Calif.

Application November 27, 1943, Serial No. 511,962

4 Claims. (Cl. 280—33.15)

This invention relates to new and useful improvements in couplings such as can be employed in coupling gliders to aircraft, between trailers and drawn implements and vehicles, as a bomb release and for various other purposes.

The principal object of the present invention is to provide a self-locking coupling which can be easily released by remote control.

Another very important object of the invention is to provide a coupling structure which can be employed in conjunction with swordfish gaffs.

Other objects and advantages of the invention will become apparent to the reader of the following description.

In the drawings—

Figure 1 represents a side elevational view of the coupling.

Figure 2 is a top plan view.

Figure 3 is a bottom plan view.

Figure 4 is a longitudinal sectional view.

Figure 5 is a cross-sectional view on line 5—5 of Figure 1.

Figure 6 is a cross-sectional view on line 6—6 of Figure 2.

Figure 7 is a top plan view of the unit.

Figure 8 is a bottom plan view of the shutter plate.

Figure 9 is a fragmentary longitudinal sectional view showing a modified form of coupling used in conjunction with a fish gaff.

Figure 9a is a fragmentary elevation of the free end of the handle shown in Figure 9.

Figure 10 is a fragmentary front elevation of the fulcrumed plate.

Referring to the drawings, wherein like numerals designate like parts, it can be seen that reference character 5 may be considered as a tractor or aircraft, having a member 6 attached thereto to which, by simple means 7 a connection 8 is established between the member 6 and the coupling unit, generally referred to by numeral 9, and which forms the present invention.

This unit comprises an elongated barrel 10 having a solid body 11 therein secured to the barrel 10 by a bolt, or the like 12.

A plug 13 is threadedly disposed into one end of the barrel 10 and is secured in place by a bolt or like member 14.

In the other end of the barrel 10 is a longitudinally extending partition 15, which, in the form shown in Figure 4, has a pair of tapered openings 16, 16 in the outer end portion thereof. The partition 15 is fixed and defines a pair of slideways 17, 18, the first for a slide block 19 and the lat-

ter for the reception of a slide body 20, at the outer end of which is a coupling tongue 21.

This end portion of the barrel 10 has an eye 22 and a complementary eye 23 is located on the slide body 20 outside of the barrel 10. A chain bracket (see Fig. 3) connects the eyes 22, 23 and, in this connection, a snap fastener 25 may be employed. This chain serves to limit the outward movement of the tongue 21.

10 The slide block 19 has a pair of recesses 31, 31 at the underside thereof which are capable of matching the tapered openings 16, 16.

A shutter plate 32 having a pair of openings 33, 33 therein for receiving balls 34, 34 is provided with a depending head 35 between which and the adjacent end of the fixed body 11 a coiled compression spring 36 is located. It will here be noted that the portions of the shutter plate 32 inwardly of the openings 33 are bevelled so that 15 the balls 34 will be scooped out of depressions in the top of the slide body 20 as the slide body 20 is moved outwardly by the pressure of the spring 36.

The tongue 21 may be released manually by 20 the operation of an elongated control rod 38. This rod extends through bores in the body 11 and plug 13 and has a finger grip 39 at its outer end. The inner end of the rod 38 connects to the slide block 19 and a spring 40 is provided on this 25 end portion and interposed between the slide block 19 and the body 11.

As can be seen in Figure 5, the outer end of the slide block 19 is in the path of the swingable plate 28, this plate having an opening 41 at its 30 upper end through which can be looped, as at 42, one end of a control cable or line 43.

The plate 28 is formed with upstanding ears 28' between which the loop 42 passes, this loop 35 also passing through an opening 28b. The upper end of the plate is rolled to protect the rope 43.

It can now be seen the tongue 21 is engaged with some structure to be drawn, the slide body 20 is forced inwardly so that the balls 34, 34 are 40 removed from the recesses 31, 31 in the slide block 19, thus acting to interlock the slide body and prevent return of the tongue 21.

When it is desired to release the tongue 21, a pull either on the manual control rod 38, or on 45 the remote control line 43, will result in an inward movement of the block 19. This will result in the matching of the recess 31, 31 with the balls 34, thus permitting the shutter plate 32 to act on the balls 34, 34 forcing the balls upwardly 50 to the recesses 31, 31 and freeing the shutter plate 55 to the recesses 31, 31 and freeing the shutter plate

and the slide body 20 so that the spring projects the tongue outwardly.

A knob 45 is situated on the top of the barrel 10 just above the slide block 19 and is rotatable on a pin 46 which is disposed through spring 48 in knob 45 through slot 47 which is threaded into the slide block 19. Pin 46 has a locking pin 44 disposed through pin 46 in slot 47 in the adjacent end of the barrel 10, barrel 10 is formed to define a shoulder 50. The knob 45 can also be used as a release.

It can now be seen that the knob 45 can be lifted and rotated to a transverse position where it will abut the shoulder 50 and this will prevent retraction of the slide block 19 and release of the tongue 21.

A modification of the invention is shown in Figure 9 wherein a body 11a is provided with a tubular shell 10a projecting beyond one end and having a longitudinal partition 15a therein serving to provide guideways for a slide block 19a and a slide body 20a, the slide body 20a having cooperative therewith a shutter plate 32a corresponding to the shutter plate 32, but having only one opening 33a therein.

The partition 15a has but a single tapered opening 16a and the slide block 19a but a single recess 31a.

The slide body 20a has a slot 26a therein through which a pin 27a is disposed and on this is a plate 28a free to swing and having connected thereto a control cable or line 43a, this plate 28a being adapted to operate against the slide block 19a. The slide block 19a is operative against the compression spring 40a while the shutter plate 32a has a depending portion 35a between which and the adjacent end of the fixed body 11a a compression spring 36a is interposed.

The line 43a extends longitudinally of the body 11a and is engaged by a spring clip 43b.

The only substantial difference between this form of the invention and the form shown in Figure 4, is that instead of a tongue 21, this form of the invention carries a gaff hook 21a such as is used in the fishing industry.

Obviously, any number of balls 34 or 34a may be employed.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A device of the character described comprising a body structure, a retractable coupling element, said coupling element having a shank longitudinally slidable in the body, a slide block in the body, said block having a recess or recesses, a spring biasing said block outwardly with respect to said body, said shank having a recess or recesses, a ball or balls interposed between the shank and body block, and means for shifting the block against the bias of said spring so that its recess or recesses will match the ball or balls to release the shank with respect to the body.

2. A device of the character described comprising a body structure, a retractable coupling element, said coupling element having a shank longitudinally slidable in the body, a slide block in the body, said block having a recess or recesses, a spring biasing said slide block said shank having a recess or recesses, a ball or balls interposed between the shank and body block, and means for shifting the block against the bias of said spring so that its recess or recesses will match the ball or balls to release the shank with respect to the body.

15 3. A device of the character described comprising a body structure, a retractable coupling element, said coupling element having a shank longitudinally slidable in the body, a slide block in the body, said block having a recess or recesses, a spring biasing said slide block said shank having a recess or recesses, a ball or balls interposed between the shank and body block, and means for shifting the block against the bias of said spring so that its recess or recesses will match the ball or balls to release the shank with respect to the body, and latch means for holding the slide block against movement.

20 4. A device of the character described comprising a body structure, a retractable coupling element, said coupling element having a shank longitudinally slidable in the body, a slide block in the body, said block having a recess or recesses, a spring biasing said slide block, said shank having a recess or recesses, a ball or balls interposed between the shank and body block, and means for shifting the block against the bias of said spring so that its recess or recesses will match the ball or balls to release the shank with respect to the body, and latch means for holding the slide block against movement, said latch means including a member pivotally mounted in said shank and abutting said slide block.

25 5. A device of the character described comprising a body structure, a retractable coupling element, said coupling element having a shank longitudinally slidable in the body, a slide block in the body, said block having a recess or recesses, a spring biasing said slide block, said shank having a recess or recesses, a ball or balls interposed between the shank and body block, and means for shifting the block against the bias of said spring so that its recess or recesses will match the ball or balls to release the shank with respect to the body, and latch means for holding the slide block against movement, said latch means including a member pivotally mounted in said shank and abutting said slide block, and remotely controlled means for releasing said latch means.

ROBERT JAMES BROWN.
